BEDSTEAD FOR CHILDREN

Ronald L. Magram, 9631 SW. 77th Ave., Apt. 208C,
South Miami, Fla. 33143

Filed Oct. 5, 1970, Ser. No. 25,329

Term of patent 14 years

Int. Cl. D6—01; D21—01

U.S. Cl. D5—4

FIG. 1

FIG. 2

FIG. 3

FIG. 4

FIG. 5

FIG. 1 is a side elevation of a bedstead for children showing my new design.

FIG. 2 is a front elevation thereof.

FIG. 3 is a rear elevation thereof.

FIG. 4 is a top plan view thereof.

FIG. 5 is a bottom plan view thereof.

I claim:

The ornamental design for a bedstead for children, as shown.
